FUEL BURNER CONTROL MEANS

Edward J. Doucet, Detroit, Mich., assignor to Detroit Lubricator Company, Detroit, Mich., a corporation of Michigan

Application May 9, 1942, Serial No. 442,290

9 Claims. (Cl. 236—10)

This invention relates to new and useful improvements in heating apparatus and more particularly to safety means for controlling the operation of the burner of the apparatus in the event an undesirable high temperature of the apparatus should occur.

The invention is particularly adapted for use in connection with floor furnaces wherein the outlet for the heated air might be obstructed as, for example, by the placing of a rug over the same and which would therefore result in a dangerous temperature of the heating apparatus, presenting a fire hazard. It is therefore one object of this invention to provide novel means which will be certain in operation for shutting down the burner in the event the temperature of the apparatus reaches an undesired high degree.

Another object of the invention is to provide a safety means which is particularly adapted for use with the control means of gravity fed liquid fuel burners.

Another object is to provide a construction in which a single temperature responsive means may be employed to regulate the operation of the burner by controlling fuel flow and also to actuate the safety means.

The invention consists in the cooperative relation and in the construction of parts which is more fully described hereinafter and the novelty of which will be particularly pointed out and distinctly claimed.

In the accompanying drawings to be taken as a part of this specification there is fully and clearly illustrated a preferred embodiment of the invention in which drawings:

Figure 1 is a view in vertical central section of a floor furnace having the safety control means of this invention operatively related thereto;

Fig. 2 is a top plan view of the control device of Fig. 1;

Fig. 3 is a view in vertical section on the line 3—3 of Fig. 2 looking in the direction of the arrows, and

Fig. 4 is a detail view in end elevational looking from right to left facing Fig. 3.

In the accompanying drawings, the numeral 1 designates generally a floor furnace type of heating apparatus mounted upon a base 2 which may be the cellar floor. Within the furnace 1, there is a combustion chamber 3 and a combustion products outlet 3^a and an air heating bonnet 4. The combustion chamber 3 has a fluid fuel burner 5 positioned in an air supply duct 6 having an air inlet opening 7. Surrounding the chamber 3 and bonnet 4 there is a cylindrical

partition 8 providing an upflow passage or duct 8^a for air to be heated and having an outlet opening 9 through a grill 10 forming part of the floor 11 of the space 12 to be heated by the apparatus. The furnace jacket 13 surrounds and is spaced from the partition 8 and cooperates therewith to provide a downflow passage 14 for air to be heated. The passage 14 has its inlet 15 opening through the grill 10 from the room or space 12 and communicates at its lower or outlet end through an annular chamber 16 with the inlet to the upflow duct 8^a.

Positioned in the chamber 16 there is a constant liquid level device 17 supported by partition 18. Liquid fuel is supplied to the device 17 through an inlet pipe or conduit 19 leading from a supply tank (not shown) and is fed to the burner 5 through a pipe or conduit 20 leading from the device 17.

The device 17 has a constant level chamber 21 provided by a casing 22 having an inlet passage 23 connected to the conduit or pipe 19. The passage 23 discharges into the chamber 21 through an inlet port controlled by a float operated valve 24 controlled by a float actuator 25, as is well known in the art. Cooperable with the valve 24 there is a safety mechanism 26 having a lever 27 for moving the valve 24 to closed position upon the occurrence of excess liquid level in the chamber 21. The lever 27 is pivotally supported at 28 and is urged toward valve closing position by an helical coil spring 29 which is held under compression between an end portion or arm 30 of the lever and a bracket 31 carried by the casing 22. The lever 27 has an end portion 32 extending external of the casing 22 through a slot 33 in the casing wall. Secured on the lever 27 adjacent the end portion 32 there is a latch plate 34 which seats on the lip 35 of a trip lever 36 to hold the lever 27 against the valve closing movement by the spring 29. The spring 29 which is in a slightly overcenter downward position holds the plate 34 in engagement with the lip 35. The lever 36, pivoted at 37, has an arm 38 positioned 45 for engagement by an extension 39 on the lever 40 having a counter-weight 40^a and which interconnects the float 25 and inlet valve 24. The lever 36 has a trip arm 41 which extends through the slot 33 to the exterior of the casing 22 and 50 which is positioned above the lever end portion 32 so that the arm 41 can be moved downward to release the latch plate 34 without interference with the lever extension 32. It may be noted that the bearing for the float arm 40 is provided with lost motion so that the float can have over travel

upon resistance to closing movement of valve 24 in order for the float to respond to excess liquid level and move the extension 39 into tripping engagement with the latch arm 38.

The pipe or conduit 20 is connected to the outlet port 42 of the chamber 21 as shown in Fig. 3. Controlling flow of liquid fuel to the burner 5 through the port 42, there is a longitudinally slid able metering valve 43 which is urged toward open position by a helical coil spring 44 surrounding the valve member 43 and held under compression between the casing 22 and an abutment or flange 45 rigid with the stem 46 of the valve member 43. The stem 46 extends upward through a guide aperture 47 in the cover member 48 of the casing 22.

Mounted on the top face of the cover member 48 there are longitudinally spaced bearing brackets 49, 50 through which there is journaled an operating shaft 51. Journaled on the shaft 51 in overlying relation to the valve stem 46, there is an operating lever 52 which is engageable with the top end of the stem 46 to move the valve member 43 toward closed position against the force of spring 44. The lever 52 carries an adjustable stop member 53 in the form of a screw which is engageable with the top face of the cover member 48 to limit downward movement of the stem actuating end of the lever 52 thereby to determine the extent of valve closing movement and to determine the minimum flow position of the valve member 43 for maintaining a pilot or low flame in the burner 5. Opening movement of the valve member 43 is determined by a maximum flow adjustment screw 54 which is adjustably screw-threaded in an extension 55 of the bracket 49 and which has its bottom end engageable with the top face of lever 52 to limit its upward movement and therefore the extent of upward movement of the valve member 43. The lever 52 is operated by thermostatic means 56, preferably a helical coil bimetal strip which surrounds the shaft 51 and has one end secured as at 57 to the lever 52 and its other end 58 secured to the shaft 51 through a friction slip clutch 59. The bimetal coil 56 tends to coil up more tightly on temperature increase and therefore with the coil end 58 held against movement, the end 57 will rotate the lever 52 counterclockwise facing Fig. 4 so as to move the valve member 43 toward closed position. The shaft 51 has an end portion 60 which extends beyond the casing 22 and into overlying relation to the lever arm 41. Rigidly fixed on the shaft end 60 there is an operating cam 61 having at its lower edge an inclined cam surface 62 engageable with the upper horizontal edge of the arm 41. A spring 63 anchored at one end to the cam member 61 and its other end to the cover member 48 is under tension to resist operation of the cam member 61 and rotation of the shaft 51. The cam member 61 is normally held against a stop member or lug 64 on the cover member 48 by the spring 63 and is limited in its clockwise tripping movement (facing Fig. 4) by a stop member or lug 65 carried by the cover member 48.

The operation of the apparatus is as follows: Assuming that the burner 5 is operating to supply heated air through the outlet 9 to the space 12, the control device is shown in Figs. 3 and 4 in the position wherein the temperature of the room or space has reached the desired predetermined degree so that the return air in duct 14 to which the thermostat means 56 is subjected has caused

the thermostatic means 56 to wind up and move the metering valve 43 to its low flow position for pilot flame at the burner 5. When the temperature of the return air entering chamber 16 from passage 14 decreases, showing a demand for heat in the space 12, then the thermostatic means 56 will unwind in accordance with the decreasing temperature and rotate the lever 52 upward or clockwise facing Fig. 4. Accordingly, the metering valve 43 will move toward open position under force of the spring 44, thereby supplying fuel with a greater flow rate to the burner 5 to provide the necessary high flame for heating the space 12. This movement of the lever 52 will occur since the cam member 61 is against the stop member 64, and therefore the shaft 51 is held against rotation by the thermostatic means 56. As long as the grill 10 is sufficiently unobstructed so that a proper and adequate circulation of air can take place through the return and heating ducts 14, 8 respectively, the thermostatic means 56 will act to maintain a desired temperature in the space 12. If, however, the grill 10 should be covered as by the placing of a rug thereover, for example, and sufficient to prevent proper circulation of air to be heated through the furnace 1, then the temperature in the chamber 16 will increase to the maximum return air temperature at which thermostatic means 56 moves the valve member 43 to pilot flow position, as shown in Fig. 3. Since the air heated by the pilot or low burner flame and heated by the residual heat in the combustion chamber 3 and bonnet 4 is trapped in the furnace 1, the temperature in the chamber 16 will rise rapidly above the predetermined temperature to which valve member 43 is moved to minimum open position. The thermostatic means 56 will accordingly exert an increased force and since the coil end 57 is now held against movement, this increasing force will act through the coil end 58 to rotate the shaft 51 clockwise facing Fig. 4, thereby moving the cam surface 62 across the projecting arm 41 of the trip lever 36 and by its cam action rotating the trip lever clockwise facing Fig. 3 about its pivot 31. This movement of the trip lever 36 will release the spring 29 so that the safety mechanism 26 will move the inlet valve 24 to full closed position. The quantity of oil or liquid fuel remaining in the chamber 21 will continue to flow to the burner 5 but with a decreasing head pressure so that the flame in the burner 5 will gradually decrease and become extinguished in a relatively short time period. Accordingly, fire hazard will be eliminated by extinguishment of the burner. In order to restart the burner, it is necessary after the cam member 61 has been retracted to the position of Fig. 4 by cooling of the thermostatic means 56, to manually lift the lever extension 32 until the latch plate 34 again rests on the lip 35 as shown in Fig. 3. Oil will now again be permitted to flow to the burner 5 and may be reignited in the usual way to again place the heating apparatus in operation.

Having thus described the invention, what is claimed and is desired to be secured by Letters Patent of the United States is:

1. In a heating apparatus, a fluid fuel burner, means for supplying fuel to said burner, a longitudinally slid able metering valve for regulating the supply of fuel, a safety valve operable to stop the supply of fuel, a spring urging said metering valve toward open position, thermostatic means responsive to the temperature of a medium heated

by said burner, means operatively connecting said thermostatic means to said metering valve so that upon temperature increase of said medium, said thermostatic means will move said metering valve toward closed position, force exerting means tending to move said safety valve to closed position, releasable means holding said force exerting means against movement, means actuated by said thermostatic means to release said releasable means, means to limit closing movement of said metering valve by said thermostatic means thereby to maintain a reduced burner flame, and a spring opposing operation of said releasable means with a force greater than the force of said metering valve spring so that an increase in temperature of said medium above the temperature at which said limiting means opposes said metering valve is required for operation of said releasable means by said thermostatic means.

2. In a heating apparatus, a liquid fuel burner, a constant liquid level device having a float operated inlet valve and an outlet to said burner, excess liquid level operated safety means for moving said inlet valve to closed position, a metering valve controlling said outlet and movable between maximum and minimum open positions to provide high and low burner flames, thermostatic means mounted on said device and responsive to the temperature of a fluid medium heated by said burner, means operatively connecting said thermostatic means to said metering valve to move said metering valve to minimum position upon occurrence of a predetermined high temperature of said medium, means operable by said thermostatic means to actuate said safety means, and means opposing operation of said safety means by said thermostatic means with a force sufficient to require a temperature increase of said medium above said predetermined temperature prior to operation of said safety means by said thermostatic means.

3. In a heating apparatus, a constant liquid level device having an outlet for supplying fuel to a burner, a vertically slidable metering valve controlling said outlet, safety means for stopping the admission of fuel to said device, an operating shaft rotatably mounted on said device, a lever journaled on said device and operable to actuate said metering valve, a bimetal coil thermostatic means having one end secured to said lever and having its other end secured to said shaft, means operable upon rotation of said shaft by said thermostatic means to actuate said safety means, and means resisting rotation of said shaft by said thermostatic means so that said thermostatic means initially actuates said metering valve.

4. In a heating apparatus, a floor furnace having inlet and outlet openings for return and for flow of heated air from and to the space to be heated, a liquid fuel burner for heating the air supplied to said outlet opening, a constant liquid level device an inlet and having an outlet for supplying fuel to said burner, a float operated valve controlling said inlet, a metering valve controlling said outlet, safety means to close said inlet valve for stopping the admission of fuel to said device, thermostatic means responsive to the temperature of said furnace, means directly and positively mechanically connecting said thermostatic means to said metering valve, said thermostatic means moving said metering valve to a minimum flow position at a predetermined high furnace temperature, means directly operable by the force of said thermostatic means at an increased temperature above said high temperature

5 to actuate mechanically said safety means, and means determining the temperature differential between the high temperature for movement of said metering valve to said minimum position and the increased temperature for actuation of said safety means.

10 5. In a heating apparatus, a constant liquid level device having an inlet and having an outlet for supplying fuel to a burner, a float operated valve controlling said inlet to maintain a substantially constant liquid level, a safety lever engageable with and operable to seat said valve, means urging said lever in a valve seating direction, a latch holding said lever against movement by said urging means, float operated means engageable with and operable to release said latch upon occurrence of liquid level above said constant level, a metering valve controlling said outlet, thermostatic means operable to move said metering valve toward closed position, and means operable by said thermostatic means to release said latch.

15 6. In a heating apparatus, a constant liquid level device having an inlet and having an outlet for supplying fuel to a burner, a float operated valve controlling said inlet to maintain a substantially constant liquid level, a safety lever engageable with and operable to seat said valve, means urging said lever in a valve seating direction, a latch holding said lever against movement by said urging means, float operated means engageable with and operable to release said latch upon occurrence of liquid level above said constant level, a metering valve controlling said outlet, thermostatic means operable to move said metering valve toward closed position, means to limit closing movement of said metering valve, means operable by said thermostatic means to release said latch, and means requiring an increased temperature of said thermostatic means to operate said last-named means subsequent to operation of said limiting means.

20 7. In a heating apparatus, a constant liquid level device having a chamber with an inlet and with an outlet for supplying fuel to a burner, a valve controlling said inlet, means responsive to liquid level in said chamber and operatively connected to said valve to maintain a substantially constant liquid level in said chamber, safety means operable to move said valve to closed position, means operable to actuate said safety means to close said valve upon occurrence of a liquid level in said chamber above said constant level, metering means controlling flow from said outlet, thermostatic means operable to actuate said metering means, and means operable by said thermostatic means to actuate said safety means to close said valve.

25 8. In a heating apparatus, a constant liquid level device having a chamber with an inlet and with an outlet for supplying fuel to a burner, a valve controlling said inlet, means responsive to liquid level in said chamber and operatively connected to said valve to maintain a substantially constant liquid level in said chamber, safety means operable to move said valve to closed position, means operable to actuate said safety means to close said valve upon occurrence of a liquid level in said chamber above said constant level, metering means controlling flow from said outlet, thermostatic means responsive to temperature of a medium heated by the burner and operable to actuate said metering means to reduce flow from said outlet upon temperature increase of the medium, means operable by said thermostatic means

to actuate said safety means to close said valve, and means resisting operation of said last-named means by said thermostatic means thereby to require the medium to have a predetermined high temperature for operation of said last-named means.

9. In a heating apparatus, a constant liquid level device having a liquid fuel chamber with an inlet and an outlet for supplying fuel to a burner, a valve operable to shut said inlet, safety means engageable with and operable to shut said valve, means actuated by an increased liquid level above the constant liquid level in said chamber, releasing means operable by said actuated means to

actuate said safety means, a metering valve controlling flow from said outlet, thermostatic means operable to actuate said metering valve, means to limit closing movement of said metering valve by said thermostatic means, means for continued movement of said thermostatic means upon temperature increase above the temperature at which said metering valve is limited by said limiting means, and means operable by such continued movement of said thermostatic means and operable to actuate said releasing means thereby to shut said inlet valve.

EDWARD J. DOUCET.
